UNITED STATES PATENT OFFICE

2,590,195

ADJUSTABLE SHELF

Arthur G. Merkle and Hoxie Eldridge, Marshall,
Mich., assignors to Sherer-Gillett Company,
Marshall, Mich., a corporation of Illinois

Application November 21, 1947, Serial No. 787,464

4 Claims. (Cl. 248—245)

1

Our invention relates to improvements in adjustable shelf brackets and is especially adapted for use in connection with commercial display cases and the like in which meat and other commodities are stored, displayed, and from which they are sold.

One object of our invention is to provide a bracket which may be mounted on the display cabinet or case which will be strong and rigid enough to support the scales used in dispensing goods and wherein the guide of the scale, bracket or shelf may be adjusted at the will of the operator.

Other objects will appear from time to time in the specification and claims.

The invention is illustrated more or less diagrammatically in the accompanying drawings, wherein:

Figure 1 is a diagrammatic rear elevation of a display counter;

Figure 2 is a side elevation of the bracket;

Figure 3 is a vertical section through a part of the counter showing the bracket in elevation and a shelf supported on the bracket;

Figure 4 is a plan view of the bracket;

Figure 5 is a section along the line 5—5 of Figure 3;

Figure 6 is a section along the line 6—6 of Figure 3 on an enlarged scale showing the parts before actual locking has taken place;

Figure 7 is a similar section showing the parts in position after locking has occurred.

Like parts are indicated by like characters in the specification and drawings.

1 is a display cabinet having a forwardly inclined rear wall 2, a work opening 3 closed by a removable door 4. At some place on this forwardly inclined wall 2, shown in this case adjacent one end, is mounted a plate 5 held on the wall by screws 6. The plate is integrally channelled along each side as at 7, the channels, where they overhang the plate, being notched at 8, 8 on both sides of the plate.

9 is a slide plate of such width and thickness as to rest on the plate 5 and slide within the channels 7. Integral with this plate is a horizontally disposed bracket plate 10. Plates 9 and 10 are joined as at 11 and are so disposed with respect to the angle of the plate 5 and the back of the counter or box 1 that when the plate 9 travels in the channel 7, the plate 10 is substantially horizontal. The plates 9 and 10 are, before they are bent in the position shown in Figure 2, notched at 12 so that the plate 10, being wider than the space between the inner edges of the

2

channels 7, is still free to travel up and down along the plate 5. 13 is a strut plate whose width is less than the distance between the inner edges of the channel 7. The strut is welded or otherwise suitably attached, as at 14 and 15, to the plates 10 and 9, respectively. 16 is a locking plate hinged at 17 to the underside of the plate 10, having an angular extension 18 adapted to engage the notches 8, 8. The locking plate 16 carries two shoulders 24 which extend beyond the angular extension 18, and when that extension engages the notches 8, 8 it is adapted to be thrust into engagement with the plate 5, where it is recurved to define the channel 7 by the spring 19 which urges the plate 16 in a clockwise direction as indicated in Figure 3. The width of the angular extension 18 is such that when the shoulders 24 engage the plate 5, the extension 18 does not at first engage the plate 9 as the device is being manually placed in position. However, when load is applied to the plate 10 through the medium of the shelf 21, for instance, this tends to draw the plate 9 tightly against the outer portion of the channels 7 as indicated in Figure 7, thus not only locking the plate 9 against downward movement, but clamping it against the recurved portion of the plate 5 where the channels 7 are formed, to lock the plate 9 against all play or wobble.

When desired, the slide is disengaged from the notches 8 by merely lifting the plate 10 and shelf 21. This elimination of all play or wobble is of the utmost importance, especially when, as is frequently the case, the shelf 21 serves as a support for scales and the like.

21 is a shelf, preferably wood, extending along the back of the counter or box and supported by the plate 10. The shelf may be balanced on the plate, or there may be a plurality of such plates spaced along the box to support the shelf. The shelf is thus useful for serving or handling meat and the like, or for supporting a scale, or for any other purpose where a rigid, stiff, adjustable horizontal shelf is required.

It will be realized that although we have illustrated and described an operative device, still many changes may be made without departing materially from the spirit of our invention, and we wish, therefore, that our showing be taken as in a broad sense illustrative and diagrammatic rather than limiting us to our precise showing.

We claim:

1. A flat base plate having inwardly turned transversely slotted channel forming edges, a slide plate mounted for adjustable movement along the base plate with its opposed edges masked

by the channel forming edges of the base plate, a shelf supporting member of such width that it clears the channel forming edges extending laterally from the upper portion of the slide plate, an inclined strut of such width that it clears the channel forming edges, joining the lower portion of the slide plate and the outer portion of the shelf supporting member and a latch pivoted on the underside of the shelf supporting member adapted to overlie the channel forming edges, and penetrate two of the slots in the channel forming edges.

2. A flat base plate having inwardly turned transversely slotted channel forming edges, a slide plate mounted for adjustable movement along the base plate with its opposed edges masked by the channel forming edges of the base plate, a shelf supporting member of such width that it clears the channel forming edges extending laterally from the upper portion of the slide plate, an inclined strut of such width that it clears the channel forming edges, joining the lower portion of the slide plate and the outer portion of the shelf supporting member and a latch pivoted on the underside of the shelf supporting member adapted to overlie the channel forming edges, and penetrate two of the slots in the channel forming edges, and yielding means for biasing the latch into such penetrating engagement.

3. A flat base plate having inwardly turned transversely slotted channel forming edges, a slide plate mounted for adjustable movement along the base plate with its opposed edges masked by the channel forming edges of the base plate, a shelf supporting member of such width that it clears the channel forming edges extending laterally from the upper portion of the slide plate, an inclined strut of such width that it clears the channel forming edges joining the lower portion of the slide plate and the outer portion of the shelf supporting member and a latch pivoted on the underside of the shelf supporting member adapted to overlie the channel forming edges, the latch plate having a portion adapted to penetrate each of an opposed pair of slots in opposite channel forming edges and yielding means for biasing the latch into engagement with the channel forming edges.

4. A flat base plate having inwardly turned transversely slotted channel forming edges, a slide plate mounted for adjustable movement along the base plate with its opposed edges masked by the channel forming edges of the base plate, a shelf supporting member of such width that it clears the channel forming edges extending laterally from the upper portion of the slide plate, an inclined strut of such width that it clears the channel forming edges joining the lower portion of the slide plate and the outer portion of the shelf supporting member, a latch pivoted on the underside of the shelf supporting member adapted to overlie the channel forming edges, the latch plate having a portion adapted to penetrate each of an opposed pair of slots in opposite channel forming edges and yielding means for biasing the latch into engagement with the channel forming edges, the portion of the latch plate which penetrates the slots being adapted to clear the slide plate when the plate engages the undersides of the channel forming edges.

ARTHUR G. MERKLE.
HOXIE ELDRIDGE.
